METHOD OF HARDENING METAL STRIPS

Original Filed May 3, 1927

UNITED STATES PATENT OFFICE

CONRAD SCHUMACHER, OF LYNNBROOK, NEW YORK, ASSIGNOR TO AUTOSTROP PATENTS CORPORATION, OF DOVER, DELAWARE, A CORPORATION OF DELAWARE

METHOD OF HARDENING METAL STRIPS

Application filed May 3, 1927, Serial No. 188,427. Renewed July 2, 1929.

The invention relates to an improved method of hardening or chilling continuous lengths of heated steel strips as they pass from a heating furnace.

An object of the invention is to maintain a heated strip in contact with successive chilling or cooling plates as the strip travels from a furnace to chill the strip to approximately a desired temperature, and at the same time to keep the strip in a flat condition and prevent it from bending or warping while chilling and to maintain said chilling plates at approximately a constant temperature.

Another object of the invention is to chill different portions of the heated strip to different degrees of hardness as the strip travels between the chilling plates. A feature of the invention is that the harder portion or portions of the strip may be ground for producing one or more cutting edge or edges thereon, and a soft portion may be perforated, the invention being particularly applicable in the manufacture of safety razor blades, and other tools and articles.

The invention embodies novel features of improvement more fully hereinafter set forth and then pointed out in the claims.

Reference is to be had to the accompanying drawings forming a part hereof, wherein

Fig. 1 is a perspective view illustrating an apparatus adapted for carrying out the invention;

Fig. 2 is an enlarged longitudinal section through the steel-chilling devices, substantially on the plane of line 2, 2, in Fig. 3;

Fig. 3 is a cross section substantially on line 3, 3, in Fig. 2;

Fig. 4 is a perspective detail view, partly in section, illustrating lower chilling plates;

Fig. 5 is a detail perspective view illustrating superposed plates, and

Figs. 6, 7 and 8 are detail perspective views of modified forms of chilling plates for chilling strips to different degrees of hardness in different parts of the strips.

Similar numerals of reference indicate corresponding parts in the several views.

The numeral 1 indicates a furnace which may be of any suitable or desired character adapted to heat a metal strip A to an appro-

priate temperature, such as a relatively thin flexible strip of steel, as the same travels through the furnace. The strip may be propelled through the furnace and wound by means of a reel B which may be operated at 55 desired speed in any suitable way, such as by means of belt and pulley C, D. Other suitable propelling means for strip A may be used. Closely adjacent to the furnace are chilling plates 2 and 3 superposed and between 60 which the strip A may be propelled. By preference there are several pairs of chilling plates 2 and 3 spaced apart along the strip with spaces at 4 between each pair of plates, as indicated in Fig. 2. The strip A rests 65 upon the lower plates 2 and the upper plates 3 rest upon the strip so that the respective plates are in contact with the strip. The chilling plates 2 are supported on the top plate 5^a of a box or tank 5 so as to be cooled or 70 chilled by contact therewith. The upper part of box 5 is shown provided with side walls 5^b which retain the plates 2 and 3 from lateral displacement. To keep the plates 2 and 3 in 75 their proper positions so that they will not be displaced lengthwise during travel of strip A therebetween the plates 2 are shown provided with lateral projections 2^a engaging the metal at adjacent sides of recesses 5' in the side walls 5^b of box 5, and the upper plates 80 3 are similarly provided with side projections 3^a to engage the metal at the sides of said recesses, (Figs. 4 and 5). The arrangement described permits the chilling plates to be removed and replaced as required for ready 85 application of strip A between the plates. The box 5 is supported in any suitable manner, as upon a table or support 6 shown having legs 7 and located adjacent to the strip delivery side of the furnace. One or more 90 jets of cooling water or fluid are projected against the inner side of the top 5^a of box 5 substantially throughout the length thereof for continuously supplying chilling water or other fluid to said top and thus in thermal 95 relation to the plates for maintaining the plates 2 in a chilled condition. A fluid supply pipe 8 enters the box 5 at one end and is provided with spaced outlets or jets 8^a on the upper surface to direct streams of cooling 100

fluid E against the box top 5^a, (Fig. 2). The tend outside of the chilling plates 2 and 3 and are shown depending from the lower corners of the tank 10, to prevent condensed moisture from reaching or engaging the strip A. When the strip A has been heated to the desired temperature it is propelled or drawn from the furnace between the chilling plates 2 and 3 at a suitable speed and contact of said plates with the strip will chill it to the desired extent as it travels. Since there are several pairs of plates 2 and 3 independent of each other and spaced apart a suitable distance each pair of plates will operate on strip A independently of any other pair of plates and thereby bending or warping of strip A as it passes between the plates is prevented, because each top plate 3 may bear independently upon relatively short portions of the strip, as distinguished from a single pair of chilling plates which are of sufficient length as to extend completely along the chilling zone of a heated strip and which have heretofore been liable to warp because subjected to heating on their inner surfaces against the heated strip and to cooling on their outer surfaces with a considerable difference in temperature between the two end portions. While the contact of the heated strip A with the adjacent surfaces of the chilling plates 2 and 3 tends to heat the plates the continuous supply of cooling fluid maintained at a substantially even temperature will keep each pair of plates at substantially relative temperatures so that the strip will emerge from between the last pair of plates at the desired hardened state or condition.

A tank 10 for cooling water or other fluid rests upon the upper chilling plates 3, the bottom 10^a of which tank is preferably flexible so that through the flexibility of said bottom each of the upper chilling plates 3 may be independently pressed by means of a weight thereon to keep each plate in desired contact with strip A. For such purpose pressure plates 11 within tank 10 are located over the corresponding chilling plates 3 to press thereon, said plates 11 preferably having spaced feet 11^a to bear on the tank bottom 10^a in spaced relation so as not to interfere with the distribution of cooling fluid on said bottom. Said plates 11 are shown pivotally connected at 12 with rods 13 depending from arms 14, to which arms the rods 13 may be attached by means of screws 15. The arms 14 are pivotally supported upon rod 16 which is carried by brackets or uprights 17 secured on table 6, whereby the arms with the respective plates 11 may be swung away from tank 10 and the plates may be returned thereto as required. Suitable weights 18 are carried by the arms 14 and may be detachably secured thereto by means of screws 19. When the parts are in the positions illustrated the weights 18 will press through the plates 11 upon the flexible bottom 10^a of tank 10 to individually press the corresponding underlying upper chilling plate 3 against strip A. The chilling water or other fluid may be supplied to the tank 10 by means of a flexible hose or other conduit 20 from a suitable source of supply, and at a desired height the tank is provided with an outlet pipe at 21 which may deliver the overflow cooling fluid from the tank into the pipe 9 or to any other receptacle, or for repumping to the tank. When it is desired to replace a strip A between the chilling plates the arms 14 may be swung outwardly carrying the corresponding weight and the plates 11 away from the box so that the latter may be lifted off of the plates 3, and said plates 3 may be removed for adjustment of a new strip A over the plates 2, and then said plates and other parts may be replaced for chilling said strip. The chilling tank 10 is shown provided with deflector plates 10^b that ex-

extending lengthwise of the plates in a central position. If it be desired that one edge portion of the strip be hardened more than another edge portion of the strip the recesses 5 2' and 3' of the corresponding plates will be located adjacent to the edge of the strip to have the lesser degree of hardness, (Fig. 6). In case it be desired that the hardness of the strip A should gradually increase in the direction from one edge toward the other the recesses 2' and 3' may be arranged as illustrated in Fig. 7, that is to say the recesses will extend substantially across the plates 2 and 3, with the widest extent at the ends next adjacent to the furnace and the edge of the recess at 2'' may extend in a diagonal or other angular direction across the plates from at or near one edge to or toward the other. If it be desired that the strip shall have its central portion hardened to the greatest degree 20 and its two edge portions hardened to a lesser degree the plates 2 and 3 may have two spaced recesses, as indicated at 2' in Fig. 8, along the sides of the plates, leaving the central portion, such as at 2°, to bear upon the strip at the ends adjacent to the furnace. When the heated traveling strip first engages the plates 2 and 3 that are next adjacent to the furnace the portion of the strip that first 25 contacts with said plates will receive an initial and continuing chilling and the portion of the strip at one side of the first named portion and that passes between the opposing recesses 2', 3' of the plates will be reduced or will drop 30 slightly in temperature below its temperature as it emerges from the furnace, (by reason of atmospheric cooling), without chilling contact with the plates, and when such portion of the strip engages the chilling surfaces 35 of the plates such portion of the strip will be initially chilled, and the chilling of all portions of the strip will continue simultaneously as it travels between the successive pairs of plates. The portion of the strip that last contacted with a pair of chilling plates will be 40 hardened to a less degree than the portion of the strip which first or initially contacted with a pair of chilling plates.

During the progress of the heated strip between the chilling plates it will be gradually reduced in temperature to the degree desired when it emerges from between the plates, and may be left to cool in that condition, or the strip may be tempered by reason of the desired degree of residue heat still in the strip. In Fig. 1 tempering plates 22, 23 are shown supported upon table 6 in such position that the strip A may pass between said plates, the upper plate 23 resting upon the strip and keeping it in contact with the plate 22 as the strip travels between the plates. Said tempering plates may be heated to any desired temperature by any suitable means, such as by means of an electrical heater, indicated 55 generally at 24.

By the means described strips of steel having different degrees of hardness may be utilized for production of tools or implements for various purposes. For instance, razor blades may be made from the strip A with the 70 longitudinal central portions of the blades of less hardness than the edge portions in accordance with Fig. 4, or with one edge portion of less hardness than the other edge, in accordance with Fig. 6, so that the harder portion or portions of the blades may be provided with cutting edges, and apertures may be punched with facility and economy in the less hardened or softer portion of the strip. Furthermore, saws may be made from some 75 of the strips with the teeth cut along the hardened edge portion, leaving the other portion of the saws of less degree of hardness. 80

Having now described my invention what I claim is:—

1. The method of hardening a strip of metal consisting in heating the strip to a desired temperature, initially chilling one portion of the strip before chilling another portion thereof that is located at one side of the first named portion, subsequently chilling both said portions simultaneously, and propelling the strip as it hardens.

2. The method of hardening a strip of metal consisting in heating the strip to a desired temperature, initially chilling a portion of the strip, and causing the temperature of another portion of the strip at one side of the first named portion to be reduced by atmospheric cooling below its temperature as it 95 emerges from the heating means, subsequently chilling both said portions simultaneously, and propelling the strip as it hardens.

3. The method of hardening a strip of metal consisting in heating the strip to a desired temperature and passing the strip between chilling surfaces, initially chilling one portion of the strip before chilling another portion that is located at one side of the first named portion thereof, and subsequently 105 chilling both said portions.
